DESIGN FOR A GAME BOARD

Arne H. Bruheim, Minneapolis, Minn., assignor to Victor Lundquist, St. Paul, Minn.

Application April 29, 1942, Serial No. 106,753

Term of patent 14 years

To all whom it may concern:

Be it known that I, Arne H. Bruheim, a citizen of the United States, residing at Minneapolis, in the county of Hennepin and State of Minnesota, have invented a new, original, and ornamental Design for Game Boards, of which the following is a specification, reference being had to the accompanying drawing forming part thereof.

Fig. 1 is a plan view of a game board showing my new design; and

Fig. 2 is an edge view of the game board.

I claim:

The ornamental design for a game board, as shown.

ARNE H. BRUHEIM,
